UNITED STATES PATENT OFFICE

2,128,896

KNOTTER.

Edward J. Abbott, Wilton, N. H., assignor to Abbott Machine Company, Wilton, N. H., a corporation of New Hampshire

Application February 12, 1936, Serial No. 63,541
Renewed November 29, 1937

31 Claims. (Cl. 289—3)

This invention relates to knot tyers, and while it involves improvements of utility in knot tyers generally, is especially applicable in connection with devices adapted to tie a true weaver's knot. 5 As is well known, a weaver's knot between two strands includes a formation in which one strand, conveniently referred to as the first strand, has an end portion which forms a bight about the second strand and lies back against itself forming a tail which protrudes from the knot in contact with and generally parallel to the first strand.

One object of the invention is to provide mechanism for positioning, cutting off and holding the strand which forms this tail in such manner that the knot will be thoroughly tightened and that the length of this tail will be accurately determined and can be made quite short. More particularly, the invention aims to provide a knot tyer in which the knot is formed by rotation of one tying bill, and in which the strand destined to form the aforesaid generally parallel tail of a weaver's knot is caught, cut and held by a device, preferably another tying bill, which moves with the knot-forming tying bill, approximately to the place where the knot is stripped from the knot-forming tying bill, and grips the aforesaid tail portion at the time of stripping the knot, thereby cooperating in the tightening of the stripped knot. A further object is to provide a simple and reliable mechanism for correlating the action of a knot-forming tying bill and such device for catching, cutting and holding the end which forms the aforesaid generally parallel tail of the knot.

Another object of the invention is to provide an improved form of mechanism, applicable to knotters generally but particularly suited to a weaver's knotter, adapted to position strands in a doubly-crossed formation, form a loop from these doubly-crossed strands, catch and hold the parts of the strands destined to form tails, cast off the loop comprised of the doubly-crossed strands over the severed end of one of the tails and draw the knot tight. A further object of invention is to provide an improved form of strand-crossing mechanism adapted to receive two strands, twist these together by rotation through an arc of 360°, and upon the completion of such rotation let the strands be free to leave the element which accomplished their twisting together.

Another object of the invention is to provide improved knotter-actuating mechanism, of general applicability but of special utility in connection with the automatic actuation of a knotter in a machine, and also of special utility in connection with the operation of a knotter such as that shown herein in which the rotary bills rotate only in one direction and must be stopped in a

predetermined position ready for a subsequent cycle of operations.

Other objects of invention and features of advantage and utility will be apparent from this specification and its drawings, wherein the invention is explained by way of example. 5

In the drawings:

Fig. 1 is a plan view of a knotter according to this invention with its actuating mechanism and cam-cover omitted; 10

Fig. 2 is a side elevation of the knotter of Fig. 1;

Fig. 3 is a side elevation of the knotter's back plate showing also the parts attached thereto;

Figs. 4 to 10 inclusive are diagrammatic views, 15 in perspective, showing in steps the action of the crossing mechanism, bills and stripper in forming and tightening a knot;

Fig. 11 is an end elevation of the knotter, showing particularly the actuating mechanism of the 20 knotter, this being shown in its inactive position;

Fig. 12 is a fragmentary view taken from the same point of view as Fig. 11, but showing the knotter-actuating mechanism in the act of driving the knotter; and

Fig. 13 is a vertical sectional view on the line 25 13—13 of Fig. 11.

Referring to Figs. 1, 2 and 3, the illustrated knotter is provided with a suitable strand guide 20 having a slot 21 in which one strand, which for convenience is referred to as the first strand and indicated in Fig. 4 by the reference character *x*, is adapted to lie, and an edge 22, against which the second strand, indicated in Fig. 4 by the reference character *y*, is adapted to lie. Mechanism indicated generally at 24, on the back of 30 the knotter, constitutes a further strand guide 35 for both the strands, and a function of these guides is to receive a pair of strands brought thereto either mechanically or manually, and to 40 position these strands for the intended operation thereon of the loop-forming, strand-severing and knot-stripping devices.

The preferred and illustrated form of means for forming the loop which becomes a knot of 45 the two strands is shown as comprising a rotary loop-forming tying bill 26, having fixed blades 21, 28 (see Fig. 10) and a cutting and holding blade 29 pivoted to the bill at 30 and equipped with extensions 31 and 32, serving as cam-fol-50 lowers to open and close the bill. The strand guides just mentioned are so arranged and shaped with reference to the loop-forming bill 26 as to cause the second strand *y* to be initially received by the shank of this bill, as indicated in 55 Fig. 4.

For the purpose of positioning, grasping and cutting the end of the first strand, destined to form the tail which protrudes from the resultant knot generally parallel to and in contact with 60

this strand, the invention provides a mechanism herein shown in its preferred form as a further rotary bill 35 rotatable about the same axis as the loop-forming bill 26 but oppositely directed. 5 As best indicated in Fig. 8, bill 35 has fixed blades 37 and 38 and a cutting and holding blade 39 pivoted thereto at 40, and equipped with cam-follower extensions 41 and 42 similar to those of the other bill. The relation of the strand guides to bill 35 is such as to guide the first strand *x* to the outer side of the bill blades keeping the strand clear of the bill shank, as shown in Fig. 4.

10 The above-described arrangement of bills is adapted for mounting in a simple U-shaped frame 15 45 (Figs. 1 and 2), the respective bill shafts 46 and 47 being rotatable in the opposite vertical elements 48 and 49 of the frame and driven through sets of gears 50, 51 and 52, 53, from a common drive shaft 54, which is also mounted in the opposite vertical frame elements 48 and 49. 20 Driving gears 51 and 53 are both twice the diameter of the respective driven gears 50 and 52, so that one revolution of drive shaft 54 causes two revolutions of bills 26 and 35. Figs. 1, 2, 3 and 4 25 show the elements of the knoter in their initial or starting position.

Crossing of the strands

The strand-crossing mechanism is shown as 30 comprising a circular disk 57 having on its periphery teeth 58 between pairs of which there extend open slots 60, 61 adapted to receive the first strand, *x*, and the second strand, *y*, respectively. A back plate 65 secured to the U-shaped 35 frame member 45 is suitably recessed to receive this circular disk 57 and to provide a converging mouth to facilitate entrance of the two strands into the slots 60 and 61. The disk 57 is further held in position by a pair of plates 67, 68 secured to the back plate 65 and suitably recessed to form a bearing for the disk 57 and to receive its teeth 58. A portion of the series of teeth 58 at the bottom of the disk 57 is exposed and meshes with a segmental driving element 69 pivoted at 70 40 to the back plate. A link 71, pivoted to the segmental element 69 at 72, is pivoted at 73 to a second link 74 which is pivotally mounted at 75 to the back plate 65. A cam follower 76 on link 74 engages a cam groove 78 on a cylindrical cam 79 which is fast on the main shaft 54. The 45 shape of cam groove 78 is such that at the start of a tying operation, the disk 57 is quickly turned through an angle of 360°. Fig. 5 shows this turning movement, the disk 57 turning in the direction of the arrow *z*, and Fig. 6 shows this 360° 50 rotation of the plate 57 as completed before the bills 26 and 35 have rotated a quarter turn. The strands, as indicated in Fig. 6, are thus arranged so that each strand crosses the other twice, the 55 crossings being close together and on the same side of the loop-forming means. This is of advantage in causing the consequent formation of a true weaver's knot rather than the so-called "granny" species of weaver's knot.

60 Forming the loop which becomes the knot and severing and clamping the tail of the second strand

Upon completion of a quarter turn of the bills, 70 the doubly-crossed strands are engaged by the loop-forming bill 26, which, with its cutting blade 29 closed, enters the space between the crossings of the strands and the plate 57 and thereupon by further rotation forms the strands into a loop 75 inclusive of the crossed portions thereof. The

two strands of the loop are each bent around the other, the loop around the tying bill 26 consisting of interengaging bends of both of the strands, as clearly indicated in Fig. 7. Upon reaching the position of Fig. 7 the pivoted cutter blade 29 has been opened inwardly of the bill by the camming action of a cam-shaped plate 80 (Figs. 1 and 2) upon the extension 32 of this blade, and further rotation of the bill to and beyond the position of Fig. 8 causes the second strand *y* to be engaged between this pivoted blade 29 and the fixed blades 27, 28.

By the time the position of Fig. 9 has been reached, the pivoted blade 29 has been closed by the camming action of the cam plate 80 on its extension 31, and the second strand *y* thereby sheared and clamped. The clamping of the second strand *y* by the blades of the bill 26 results in inclusion or insertion of the tail portion of this strand *y* inside of the knot-forming loop when the latter is stripped off the bill as now to be described.

Stripping the knot

A stripper arm in the form of a bell crank 84, pivotally mounted on the back plate 65 at 85, 25 is normally in the full line position of Figs. 2 and 3, wherein its hook-shaped end 86 lies below the level of the bottom of the yarn slot 61. A cam follower 87 on the bell crank stripper arm engages a cam groove 88 in the cam 79. The shape 30 of this cam groove 88 is such that the cam follower 87 and stripper arm dwell in their full line position of Figs. 2 and 3 until just before the bills reach the position of Fig. 9, whereupon the stripper arm is raised to the dotted line position of 35 Fig. 3, causing the hook 86 to engage the second strand *y*, pull it out of the groove 61 of the disk 57, further pull it to strip the knot-forming loop off bill 26 over the severed and held end of the 40 second strand *y*, and further pull it to tighten 45 the knot and drag the severed end out from between the blades of the bill.

The knoter herein illustrated is particularly adapted to be employed in automatic winding machines such as disclosed in the patent application of Edward J. Abbott and Joseph E. Ring, Serial No. 726,524, filed May 19, 1934, and in the patent application of Edward J. Abbott for Automatic winder, Serial No. 63,542, filed concurrently with this application. Any suitable abutment for the yarn *y* may be provided exteriorly of the knoter to provide a frictional hold on the yarn *y* to facilitate tensioning the part between the hook 86 and the bill 26. For example, any suitable part of the winding machine or automatic magazine with which the knoter is associated may have a bar, rod, or the like 130 which will overlie the strand *y* at a point beyond the plate 57 to facilitate tensioning the strand by the hook 86. Or, if desired, the hook-shaped element 60 86 may be supplemented by cooperating clamps and actuating mechanism to cause the strand engaged by hook 86 to be clamped as it is pulled, after the manner of several known forms of knotters, for example, as indicated in the United States patent to Edward J. Abbott, No. 1,868,682. Or, in using a knoter according to the present invention as a hand-operated knoter, the operative can hold the two strands exteriorly of the knoter as usual, thereby facilitating tightening 70 of the knot when hook 86 rises.

Positioning, severing and clamping the tail of the first strand

As indicated above, the preferred form of 75

means for positioning the first strand and forming and holding its tail is shown as constituted of the rotary bill 35. The pivoted cutting blade 39, initially held closed by the action of its cam-follower extension 42 of a cam-shaped plate 90 (Figs. 1 and 2), becomes open at the position of Fig. 7 by the action on its extension 41 of the same cam-shaped plate 90, the pivoted blade 39 opening outwardly away from the remainder of the bill. The first strand *x* extending from the loop-forming bill 26 to guide slot 21 lies in the path of the now open bill 35, as indicated in Fig. 8. Further rotation of the bills causes the cam-follower extension 42 of cutting blade 39 to engage the cam-shaped plate 90 and close the blade 39, severing the first strand *x* simultaneously with severance of the second strand by the blade 29 of bill 26, and clamping the severed end in the position of Fig. 9.

The pull of the stripper hook 86 in tightening the knot is resisted in part by each of the tails of the knot held in bills 26 and 35, until the stripped knot of Fig. 9 straightens out into a true weaver's knot and becomes tight, whereupon both tails are pulled from their bills simultaneously. By thus employing clamping means, such as exemplified by the two bills, to hold and apply tension to both tails until the knot is tight, it is assured that the knot will be correctly and securely tightened. The tail-severing and clamping action of the bill 35 moreover enables the first tail to be quite short, since the bill 35, moving with the knot-forming bill 26 and acting simultaneously therewith, is substantially no farther from the finally stripped knot than is the knot-forming bill 26, and the tail of the first strand will therefore normally be substantially as short as that of the second strand *y*.

Return of parts to starting position

Following the discharge of the tightened knot by the bills 26 and 35, these bills complete the remainder of their second full rotation to the starting position of Figs. 1, 2 and 4, and during this idle movement of the bills, the cam 79 acts to restore the stripper arm 84 and its hook 86, and the segmental plate 69 and the strand-crossing plate 57 to their initial positions, ready for another operation.

Actuating mechanism

The means for actuating the shaft 54 of the knitter may be of any desired structure adapted to rotate the shaft once for each cycle of operations, and when desired the actuating means can be in the form shown and described in the patent application of Edward J. Abbott for Knot tyer, Serial No. 63,540 filed concurrently herewith, such actuating mechanism being adapted to rotate the shaft one full revolution and to bring it to a stop.

For the use of the present knitter in the automatic winding machine of the patent application of Edward J. Abbott and Joseph E. Ring, Serial No. 726,524, wherein there is provided an electrical circuit designed to initiate actuation of the knitter, there can be employed the actuating mechanism of Figs. 11, 12 and 13 of the present application. Referring to these figures, the actuating mechanism is provided with a frame 100, attached by means of lugs 101 and suitable screws 101a to the side element 49 of the knitter frame. A solenoid 103 having electrical terminals 104, 105 is mounted on top of the frame 100 and has its armature 105 extending down through a hole

in the top of frame 100. A rack 106 connected to the lower end of the armature 105 terminates in a piston 107 near the bottom of a cylinder 108. Actuation of the solenoid 103 when an electric current is applied to its terminals raises the armature 105, rack 106 and piston 107. Both the upward movement of the piston and rack when the solenoid is energized and their downward movement when the solenoid is deenergized are cushioned by the cylinder 108, which is closed below the piston 107 except for a leak passage 110a controlled by an adjustable valve 110. Upward movement of the rack 106 rotates a pinion 112 which forms part of a one-tooth ratchet-wheel 113 loosely mounted on a reduced diameter portion 115 of shaft 54. A wheel 116 keyed to shaft 54 carries a pawl 117 adapted to engage the tooth of ratchet-wheel 113, with the result that an upward stroke of the solenoid armature 105 and rack 106 acts through the pinion 112, ratchet-wheel 113, pawl 117 and wheel 116 to rotate the shaft 54 one revolution, Fig. 12 showing the parts so moving in the directions of the arrows U, V, W, thereon. Upon the solenoid becoming deenergized, the armature and rack fall, the pawl 117 moving backward over the ratchet-wheel 113. A pawl 119, pivoted at 120 to the knitter frame, and a cooperating stop shoulder 122 on the wheel 116, are preferably provided to check a tendency of the wheel 116 and shaft 54 to be turned backward, and this pawl 119 and stop shoulder 122 are positioned with reference to each other so as to retain the shaft 54 in its position corresponding to the initial position of the bills and other parts of the knitter. Thus it is assured that the knitter will be ready to receive the strands and tie them without having to turn idly in a reverse direction after each tying operation.

Certain of the structure shown and described in this application is within the scope of generic claims of an application of Edward J. Abbot for Knot tyer, Serial No. 63,540, filed concurrently herewith, and none of the features of that application are intended to be claimed herein.

It should be understood that the present disclosure is for the purpose of illustration only and that this invention includes all modifications and equivalents which fall within the scope of the appended claims.

I claim:

1. A device for tying a weaver's knot in two strands, comprising means for positioning the strands to be tied, and means for forming a weaver's knot in said strands comprising two rotary bills.

2. A knot tyer having therein a rotary tying bill adapted to make a knot-forming loop in a pair of strands arranged in its path, means for tightening the knot including means for pulling the knot-forming loop from the bill, the bill being adapted to sever one of the strands and hold it while the knot-forming loop is pulled off over the held end, in combination with a rotary strand-severing and holding device cooperating with the tying bill and positioned with relation to the other strand not severed by the loop-making tying bill to sever and hold said other strand without making another knot-forming loop therein, said severing and holding device being timed to rotate in proximity to the aforesaid bill during the making of the knot-forming loop and to retain a hold on said other strand during the tightening of the knot.

3. A knot tyer having therein a rotary tying bill adapted to make a knot-forming loop in a pair

- of strands arranged in its path, means for tightening the knot including means for pulling the knot-forming loop from the bill, the bill being adapted to sever one of the strands and hold it 5 while the knot-forming loop is pulled off over the held end, in combination with a second rotary bill cooperating with the loop-making tying bill and engaging only the other strand not severed by the loop-making tying bill, said second bill 10 being so timed with relation to the first bill as to hold its strand during the tightening until the knot-forming loop has been pulled from the first bill.
4. A knot tyer having therein a rotary tying bill adapted to make a knot-forming loop in a 15 pair of strands arranged in its path, means for tightening the knot including means for pulling the knot-forming loop from the bill, the bill being adapted to sever one of the strands and hold it 20 while the knot-forming loop is pulled off over the held end, in combination with a second rotary bill cooperating with the loop-making tying bill and positioned with relation to the other strand not severed by the loop-making tying bill to sever 25 and hold said other strand without making another knot-forming loop therein, said second bill being so timed with relation to the first bill as to hold its strand during the tightening of the knot.
- 30 5. A knot tyer having therein two cooperating rotary devices each adapted to hold and sever a strand, means for disposing the strands to be tied in position for both of said strands to be made into a knot-forming loop by only one of said 35 rotary devices and for the two tail-forming portions of said loop to be caught, held and severed by respective ones of said two rotary devices, means for tightening the knot including means for casting off the knot-forming loop from its said 40 rotary device over the tail of the strand severed by that device, means for rotating said two rotary devices in unison, and means for causing the two rotary devices to discharge the severed tails of 45 the knot at substantially the same location in their cycle of rotation, the knot-tightening means being timed to tighten the knot while the two tails thereof are held by said respective rotary devices.
6. A knot tyer having therein two cooperating rotary bills each having blades adapted to hold 50 and sever a strand, means for disposing the strands to be tied in position for both of said strands to be made into a knot-forming loop by only one of said bills and for the two tail-forming portions of said loop to be caught, held and severed by respective ones of said two cooperating 55 bills, means for tightening the knot including means for casting off the knot-forming loop from its bill over the tail of the strand severed thereby, means for rotating the bills in unison and 60 means for operating the blades of the two bills in timed relation such as to discharge the two tail portions at substantially the same location in the cycle of bill rotation, the knot-tightening means being timed to tighten the knot while the two tails 65 thereof are held by said respective rotary devices.
7. A knot tyer having therein a pair of rotary bills disposed adjacent to each other and each having cooperating fixed and pivoted blades adapted to hold and sever a strand, means for 70 rotating the bills in unison, and means for operating the blades during such rotation, one bill having its pivoted blade arranged to open by inward movement and the other bill having its pivoted blade arranged to open by outward movement 75 with respect to the bill shank.
8. A knot tyer having therein a rotary tying bill, means for twice crossing a pair of strands in the path of the bill, said crossing means including a rotatable member adapted to receive the strands separately and means for imparting substantially a full revolution to the said rotatable member, means for rotating the bill to make a knot-forming loop of the twice-crossed strands, means for retaining one strand in position for it to be caught, severed and held by the bill, means 10 for severing the other strand, and means for casting the aforesaid loop off the bill over the severed end of the strand caught by said bill.
9. A knot tyer having therein a rotary tying bill including a shear blade, means for twice crossing a pair of strands in the path of the bill, means for rotating the bill to make a knot-forming loop of the twice-crossed strands, means for retaining one strand in position for it to be caught, severed and held by the bill, a second 15 rotary bill including a shear blade for severing the other strand, means for closing the blades of the bills upon their respective strands and means for casting the aforesaid loop off the bill over the severed end of the strand caught by said bill.
10. A knot tyer having therein a pair of rotary bills each having cooperating blades, means for rotating the bills in unison, means for opening and closing the blades, strand-crossing and guiding means for disposing the strands to be tied in a doubly-crossed formation in the path of one bill where it is in a closed state, and for disposing both strands in position to be intercepted thereafter by the respective bills while they are in an 30 open state, and means for casting off the knot-forming loop thus formed when both bills subsequently close.
11. A knot tyer having therein a pair of rotary bills having strand-severing blades, means for 40 rotating the bills in unison, means for opening and closing the blades, a rotary element adapted to receive a pair of strands at one side of the blades, means for rotating the said element sufficiently to cross the two strands twice in the path of one of 45 the bills where the latter is closed, so that further rotation of the said bill loops the crossed strands, guide means on the opposite side of the bills from said rotary element for securing the association of the two strands with the severing blades of the 50 respective bills after the loop-making action of the one bill, and means for casting off the knot-forming loop from its bill.
12. A knot tyer having therein a rotary tying bill, a rotary strand-crossing element at one side 55 of the bill, said strand-crossing element being adapted to retain two strands separate, and means for imparting substantially a full revolution to said rotary element to cross the strands twice in the path of said bill.
13. A knot tyer having therein a rotary tying bill, a rotary strand-crossing element at one side of the bill, said strand-crossing element comprising a disk having a pair of strand-receiving slots, and means for imparting substantially a full revolution to said rotary element to cross the strands 60 twice in the path of said bill.
14. A knot tyer having therein a rotary tying bill, a side frame element, a rotary disk associated with the side frame element, said disk having slots 70 to receive a pair of strands, and means operating in timed relation to the tying bill to rotate said disk substantially a full revolution to cross the strands twice in the path of said bill.
15. A knot tyer having therein a loop-forming 75

device and means for positioning two strands for loop-formation by said device, said positioning means including a rotary element having recesses to receive a pair of strands and means adapted to impart to said element substantially a full revolution, to cross the strands twice.

16. A knot tyer having therein a loop-forming device and means for positioning two strands for loop-formation by said device, said positioning means including a rotary disk having two slots, and a driving element adapted to impart substantially a full revolution to said rotary element, said disk having teeth adjacent to its periphery and said driving element having teeth meshing therewith.

17. A knot tyer having therein a loop-forming device and means for positioning two strands for loop-formation by said device, said positioning means including a rotary element having teeth at its periphery, a toothed driving element meshing with said teeth of the said rotary element, said rotary element having a pair of slots extending inwardly from spaces between pairs of said teeth to receive a pair of strands.

18. A knot tyer having therein a drive shaft, a rotary tying bill and a cam driven by the shaft, a rotary element adapted to receive two strands to be tied by the bill, and means whereby rotation of the cam through the initial part of rotation of the bill rotates the said rotary element substantially a full revolution.

19. A knot tyer having therein a drive shaft, a rotary tying bill and a cam driven by the shaft, a rotary element having two slots to receive a pair of strands to be tied by the bill, teeth adjacent to the periphery of said rotary element, and a toothed driving element meshing with the teeth of said rotary element and driven by said cam.

20. A knot tyer having therein a motor device, a rack reciprocated thereby, a pinion rotated by the rack, a knotter-operating shaft, and a one-way driving connection between the pinion and the knotter-operating shaft, whereby operation of the rack in one direction operates the knotter shaft and the rack is capable of return movement without operating said shaft.

21. A knot tyer having therein a motor device, a rack reciprocated thereby, a pinion rotated by the rack, a knotter-operating shaft, and a pawl and ratchet connecting the pinion and the knotter-operating shaft, whereby operation of the rack in one direction operates the knotter shaft and the rack is capable of return movement without operating said shaft.

22. A knot tyer having therein an oscillatory driving element, a knotter-operating shaft, a rotary tying bill operated by said shaft, a one-way driving connection between the oscillatory element and the shaft, permitting the driving element to rotate the shaft and knotter bill upon movement of said element in one direction, and means for checking backward rotation of the knotter-operating shaft.

23. A knot tyer having therein a solenoid, and a solenoid armature, a rack reciprocated by the armature, a knotter-operating shaft, a rotary tying bill operated by said shaft, a one-way driving connection between the armature and the shaft, permitting the armature to rotate the shaft and knotter bill upon movement of the armature in one direction, and means for checking backward rotation of the knotter-operating shaft at the position corresponding to the starting position of the knotter bill.

24. In combination, in a knot tyer, means for forming a weaver's knot, means for simultaneously severing the two strands to form knot tails, said severing means including cutting and clamping bills rotatable during the tying of the knot, and knot-tightening means acting to pull the tails from the bills simultaneously.

25. A weaver's knot tyer comprising means for forming a loop which includes two strands in the form of interengaging bends of both strands, means for simultaneously severing the two strands to form tail portions, said severing means including cutting and clamping bills rotatable during the tying of the knot, and means for tightening the loop about one only of the tail portions.

26. A weaver's knot tyer comprising means for arranging two strands in doubly crossed formation, means for looping the thus-arranged strands, means for simultaneously severing the two strands to form tail portions, said severing means including cutting and clamping bills rotatable during the tying of the knot, and means for tightening the loop about one only of the tail portions.

27. In combination, in a knot tyer, means for forming a weaver's knot and means for tightening the knot including means comprising two rotary bills acting to hold the two tail portions of the knot until the knot is tight.

28. In combination, in a knot tyer, means for forming a weaver's knot, and means for tightening the knot including clamping and severing devices acting on the two tail portions of the knot to hold them both under tension until the knot is tight, the clamping and severing devices comprising rotary bills.

29. A weaver's knot tyer comprising means for forming a loop which includes two strands in the form of interengaging bends of both strands, means for forming tail portions, the tyer including rotary clamps for the respective tail portions, one of said clamps being arranged to retain its tail portion in position to be received within the loop and the other of said clamps being arranged to retain its tail portion in position not to be received within the loop, means for closing said clamps approximately simultaneously during their rotation, and means for applying tension to both clamped tails until the knot is tightened and the tails thereby pulled from the clamps.

30. A weaver's knot tyer comprising means for forming a loop which includes two strands in the form of interengaging bends of both strands, means for causing one only of the tail portions to be received within the loop, the knot tyer including means for tightening the knot, including rotary clamps operative to hold both tail portions of the knot until the knot is tightened, and means for closing said clamps approximately simultaneously during their rotation.

31. A knot tyer comprising means for forming a loop which includes two strands in the form of interengaging bends of both strands, means for causing a tail portion of a strand to be received within the loop, the knot tyer including means for tightening the knot including separate rotary clamps operative to hold both tail portions of the knot until the knot is tight, means for rotating the clamps in unison, and means for closing said clamps approximately simultaneously during their rotation.

EDWARD J. ABBOTT.
